UNITED STATES PATENT OFFICE.

RICHARD F. HOMMEL, OF SAN FRANCISCO, CALIFORNIA.

AUTOMATIC PARACHUTE ATTACHMENT FOR AEROPLANES.

1,092,443.

Specification of Letters Patent.

Patented Apr. 7, 1914.

Application filed May 5, 1913. Serial No. 765,969.

To all whom it may concern:

Be it known that I, RICHARD F. HOMMEL, a citizen of the United States, residing in the city and county of San Francisco and State of California, have invented a new and useful Improvement in Automatic Parachute Attachments for Aeroplanes, of which the following is a specification.

My invention relates to parachutes for aeroplanes that will be automatically projected into a supporting position as soon as released and its object is to prevent the too rapid falling of an aeroplane in cases of emergency, such as when the motor is disabled or for any purpose fails to operate.

A full and clear comprehension of my invention may be had by reference to the drawings forming a part of this specification wherein like numerals of reference 20 designate similar parts throughout the said specification and drawings and in which—

Figure 1 is a broken plan view of an aeroplane composed of circular or cylindrical gas bags of stiff material connected by a central web, one of the said bags being disclosed in the figure, and one of the wings of the parachute being disclosed in an extended position. Fig. 2 is a vertical transverse sectional view disclosing my parachute 30 attached thereto in a folded position, the dotted lines indicating the extended position of one of the parachute wings.

My invention consists of folded canvases having their outer edges secured to the outer 35 ends of supporting poles which are secured within suitable channels within the gas planes. The inner edges of the canvases are secured to the gas bags so that when the poles are automatically projected the canvases will be extended from the sides of the 40 aeroplane bags in a supporting position.

Referring to the drawings the numeral 1 is used to designate the gas bags of an aeroplane which are connected by means of the central web 2 which is hollow and filled with gas. Within suitable channels 3, situated transversely to the aeroplane or bags 1, are the poles 4 having collars 4' secured thereto. Between the collars 4' and the 45 closed ends of the channels 3 the springs 5 are interposed. A lug 6 on the outer ends of the poles, is retained against the tension of the springs 5 by means of the latch 7 which is secured to the gas bag 1. These 50 latches may be released by means of the

lines 8 which extend from the said latches 7 to any suitable portion of the aeroplane where they will be within reach of the operator. Canvases or wings 9 are folded against the sides of the gas bags 1 and under a shelf 10 secured to the said bag 1. The inner ends of the said canvases are secured to the sides of the gas bags 1 while the outer edges of the said canvases 9 are secured to the outer ends of the poles 4.

When it is desired to release the wings 9 the same is accomplished by releasing the latches 7 by means of the lines 8. As soon as the latches are pulled from the lugs 6 on the poles 4 the springs 5 project the poles 4 to the position indicated in Fig. 1 of the drawings in full lines or to the position indicated by dotted lines in Fig. 2 of the drawings. As the poles 4 are projected into position the wings 9 are likewise projected into the positions indicated in full lines in Fig. 1 of the drawings and in Fig. 2 the extended position of the wings 9 is indicated in dotted lines.

It is obvious from the foregoing that I 80 have provided means for automatically projecting parachute wings into a supporting position from the sides of the aeroplane.

Having thus described my invention what I claim as new and desire to secure by Letters Patent is—

1. An automatic parachute attachment for aeroplanes comprising a plurality of transversely extending channels having one end closed, transverse poles secured within the said channels; collars secured to the poles; springs interposed between the collars on the poles and the closed ends of the channels; means for retaining the poles within the channels against the tension of the springs; canvas wings folded and secured against the sides of the aeroplane, the outer edges of the canvas wings being secured to the outer ends of the poles; and means for releasing the poles from the channels.

2. In an automatic parachute attachment for aeroplanes the combination with an aeroplane body of suitable transverse channels therein having one end closed; poles within the channels; collars secured to the poles; springs interposed within the channels and between the collars on the poles and the closed ends of the channels; lugs on the outer ends of the poles; latches secured to

the aeroplane and adapted to engage the lugs on the poles; horizontal extensions secured to the aeroplane slightly above the transverse channels therein; canvas wings 5 folded against the sides of and having their inner edges secured to the aeroplane body below the horizontal extensions and above the opening of the channels therein and the outer edges of the said wings being connected to the outer ends of the poles; and 10

means for releasing the latches from the lugs on the poles.

In witness whereof I hereunto set my signature in the presence of two subscribing witnesses.

RICHARD F. HOMMEL.
